ATTORNEY

UNITED STATES PATENT OFFICE.

CLEM S. CLARKE, OF SHREVEPORT, LOUISIANA.

CASING HEAD.

Application filed May 26, 1921. Serial No. 472,763.

To all whom it may concern:

Be it known that I, CLEM S. CLARKE, a citizen of the United States, residing at Shreveport, in the parish of Caddo and State of Louisiana, have invented new and useful Improvements in Casing Heads, of which the following is a specification.

This invention relates to improvements in casing heads for use in connection with oil wells.

An important object of the invention is the provision of hand gripping means to attach to the upper face of well tube gripping segments.

Another object of the invention is the provision of novel form of slips for holding pipe suspended within the well, the particular formation and arrangement of the slips providing a grip which engages approximately two-thirds of the circumference of the pipe and thus provides positive means for preventing the pipe from slipping downward.

Another object of the invention is the provision of means whereby the slips engage the pipe in a manner to provide a uniform pressure and thus prevent crushing or injury to the pipe, certain of the slips providing a "back up" grip which engages that portion of the pipe's circumference, or the remaining one-third not engaged by the slips above mentioned.

A further object is the provision of a casing head in which the relative size of the bore and the size of each individual slip is such as to prevent the latter from dropping through the head and thus guards against loss and possible serious injury to the well.

With the above and other objects in view, the invention further includes the following novel features and details of construction, to be hereinafter more fully described, illustrated in the accompanying drawings and pointed out in the appended claims.

In the drawings—

Figure 1 is a vertical longitudinal sectional view showing a casing head and pipe shown in connection therewith.

Figure 2 is a section on the line 2—2 of Figure 1 looking in the direction of the arrow.

Figure 3 is a detail perspective view of the slip used for preventing rotary movement of the pipe.

Figure 4 is a perspective view of a slip used for preventing downward movement.

Referring in detail to the drawings, wherein like characters of reference denote corresponding parts, the reference character 10 indicates a casing head which is shown as threadedly mounted upon the upper end of a well casing 11. The head is provided with oppositely arranged openings 12, while its bore is flared upwardly and outwardly to provide an inclined surface 13, the lower end of this inclined surface forms the most restricted portion of the bore of the head and the diameter of this portion is preferably greater than the bore of the casing 11. This is an important feature in casing head construction, in that it permits the introduction of oil well fishing tools and other equipment within the casing, without removing the head. At its upper end the head 10 is formed with an enlarged bore 14.

For the purpose of temporarily holding the pipe which is indicated at 21, in position, there is associated with the head, slips 22, 22^a and 23. The slips 22 and 22^a herein shown as two in number are provided with transversely arranged serrations or teeth 24 and these teeth are adapted to surround and engage approximately two-thirds of the circumference of the pipe to hold the same against downward movement. One of the novel features of these slips resides in coupling the slips 22 and 22^a by means of a handle or bail 25, which is pivotally secured to each slip by means of upstanding ears 25^a. The handle provides means for simultaneously positioning the slips 22 and 22^a and as the latter engage the pipe beyond each side of its center, an initial grip is provided upon the pipe prior to the insertion of a slip 23. Also, by coupling the slips 22 and 22^a, these are inserted so as to occupy the same relative positions upon opposite sides of the pipe and thus aid in centering the pipe for the proper insertion of the slip 23. This last mentioned slip is provided with vertically arranged teeth or serrations 26, which engage the pipe and act to prevent rotation of the latter when coupling or uncoupling the pipe sections. The slip 23 is preferably provided with a handle 27 by means of an upstanding ear 27^a.

The invention is susceptible of various changes in its form, proportions and minor

details of construction and the right is herein reserved to make such changes as properly fall within the scope of the appended claims.

5 Having described the invention what is claimed is:—

1. The combination with a well casing head having a tapered bore, of three tapered well tube gripping segments received in the bore, a U-shaped member pivotally connected with the upper face of a pair of segments, and a loop pivotally connected with the upper face of the remaining segment.
- 10 2. The combination with a well casing head having a tapered bore, of three co-acting tapered segments received in the bore

and adapted to clamp a well tube therebetween, alined upstanding ears carried by one pair of the gripping elements, a U-shaped member having its ends pivotally connected with the ears, an upstanding ear carried by the remaining gripping segment, and a finger engaging loop carried thereby.

3. The combination with a well casing head having a tapered bore, of a plurality 25 of tapered well tube gripping segments received in the bore, a member pivotally connected with the upper faces of a plurality of segments, and a loop pivotally connected with the upper face of another segment.

30 In testimony whereof I affix my signature.
CLEM S. CLARKE.
